UNITED STATES PATENT OFFICE

SAMUEL OLSON, OF OAK PARK, ILLINOIS, ASSIGNOR TO SAMUEL OLSON & COMPANY, INC.,
OF CHICAGO, ILLINOIS, A CORPORATION OF ILLINOIS

CONVEYER ROLL

Application filed April 5, 1930. Serial No. 441,752.

This invention relates to conveyer rolls of the "anti-friction" type, and has for an object to provide an improved roll that is simple in design, composed of relatively few parts, and which is substantial, durable and efficient in operation. Another object is to produce an improved conveyer roll which is comparatively inexpensive to manufacture. A further object is to provide an improved "anti-friction" journal bearing for conveyer rolls with a simple, compact and novel arrangement for supplying lubricant to the bearings. It consists in certain features and elements of construction, in combination, as herein shown and described and as indicated by the claims.

In the drawing:

Figure 1 is a fragmentary vertical section through a conveyer roll and its mounting, embodying my invention.

Figure 2 is a fragmentary perspective view of the conveyer roll and mounting.

Referring now in detail to the drawing: The conveyer roll, as illustrated, includes a tubular body, 10, journaled on a shaft, 11, whose ends are carried in supporting brackets, 12. Firmly secured in each end of the tubular body is a head, 13, which may be in the nature of a stamping or a casting. Adjacent each end of the tubular body there are provided a plurality of depressed portions, 15, which in effect form an internal stop shoulder, 16, against which the head, 13, abuts. It may be understood that these depressed portions are located a substantial distance from the end of the tubular body so that the heads may be formed with annular flanges, 17, of substantial width, which flanges are dimensioned for a snug fit inside the end of the tubular body and serve to reinforce the same. The heads are firmly locked in the ends of the tubular body against the stop shoulders, 16, by spinning the extreme end portions of the tubular body over the outer peripheral edges of the head; as indicated at 18.

Each head, 13, as shown in Figure 1 of the drawing, is dished in cross section to form a cavity, 19, with an internal transverse stop shoulder, 20, and has its central area further

depressed as indicated at 21, and dimensioned to fit snugly against the transverse stop shoulder, 22, on the shaft, 11. Securely mounted in the cavities, 19, of the heads are anti-friction bearings arranged to abut against the transverse internal shoulders, 20, thus effectively closing the inner cavities or chambers, 23, which are thus adapted to serve as lubricant reservoirs for the anti-friction bearings; it being understood that the lubricant is in the nature of a heavy grease.

These anti-friction bearings, as shown in the drawing, are each composed of an outer race, including a frame cup, 25, and a pair of grooved annular members, 26, in which are seated the usual series of bearing balls, indicated at 27, and an internal race, herein shown as a sleeve or bushing, 28, mounted on the reduced portion, 29, of the shaft, 11, and also grooved as indicated at 30, to form a co-operative race-way for the ball bearings, 27. This sleeve, 28, is fixed against axial movement on the shaft by abutting at one end against a transverse stop shoulder, 32, on said shaft, and against the bracket, 12, at the other end. The frame cup, 25, of the outer race is of channel cross section for embracing the two annular seat elements, 26, and has one leg abutting against the stop shoulder, 20, of the head while the outer leg of the channel extends inwardly as indicated at 25^a, and snugly fits around the sleeve, 28, thus serving to retain the lubricant in the cavity. The central portions, 21, of the heads being snugly fitted against the shoulder, 22, also tend to seal the lubricant against escape into the interior of the tubular body, 10. The reduced portions, 29, at the ends of the shaft are provided with longitudinal passageways, 33, which communicate with transverse passageways, 34, opening into the interior of the lubricant reservoir or chamber, 23. The outer ends of the shaft are provided with the usual fittings, 35, for connection to a suitable device for supplying the lubricant under pressure.

Since the annular type of anti-friction bearing shown is not designed to take end thrusts, such stresses, if they occasionally occur, are taken up by the stop shoulders, 100

- 22, of the shaft engaging the inner faces of the heads 13, and I lock each end of the shaft to its mounting bracket, 12, by means of a washer, 36, detachably secured by a machine screw, 37, to the outer face of the bracket, with a portion of the washer element, 36, engaged in a slot or groove, 38, formed in the reduced end portion, 29, of the shaft, as may be seen in Figure 1 of the drawing.
- 10 It will be manifest that a conveyer roll embodying the present invention is relatively simple, compact and capable of being manufactured at a relatively small cost. Furthermore, it will also be observed that this
- 15 construction embodies a new arrangement for lubricating the anti-friction bearings, which will greatly reduce the amount of lubricant necessary for maintenance as a supply in the reservoir, and serve to confine the
- 20 lubricant to direct and close association with the parts to be lubricated.

I claim:—

1. In a conveyer roll structure, in combination with supporting brackets, a tubular body, a shaft disposed concentrically therein and having its ends supported in said brackets, heads fixedly secured in the ends of the tubular body, each head being dished to form a cavity and an internal transverse shoulder, and anti-friction bearings for journaling the tubular body on the shaft, each including an outer race secured in the cavity and abutting the shoulder, and an inner race fitted on the shaft and arranged to abut
- 25 against a stop shoulder on the shaft at one end, and against one of the supporting brackets at the other end, each head having an inner cavity beyond its said transverse shoulder, said inner cavity encircling a part
- 30 of the shaft beyond the stop shoulder thereof, and the shaft being formed with a passageway for the introduction of lubricant leading in from the end of the shaft and opening laterally into said inner cavity of
- 35 the head.
2. In a conveyer roll structure, in combination with supporting brackets, a tubular body, a shaft disposed concentrically therein and having its ends supported in said
- 40 brackets, heads firmly secured in the ends of said tubular body, said heads being formed as pressed metal stampings dished to form an exteriorly open cavity, and including a central transverse wall fitted snugly around
- 45 said shaft, and an anti-friction bearing secured in the outer end of each cavity and arranged for journaling the tubular body on the shaft, the inner portion of the cavity serving as a lubricant chamber for the bearing, said central transverse wall of the heads being positioned in close proximity to transverse shoulders on the shaft serving to seal the lubricant chambers.

SAMUEL OLSON.
